UNITED STATES PATENT OFFICE.

JOHN MURPHY, OF COLUMBUS, OHIO.

RAILWAY-TIE.

No. 826,262.

Specification of Letters Patent.

Patented July 17, 1906.

Application filed April 19, 1906. Serial No. 312,560.

To all whom it may concern:

Be it known that I, JOHN MURPHY, a citizen of the United States, residing at Columbus, in the county of Franklin and State of Ohio, have invented certain new and useful Improvements in Railway-Ties, of which the following is a specification.

My invention relates to an improvement in railway-ties, and particularly to that class of ties which are formed of a suitable composition.

This invention is designed as an improvement upon the railway-tie shown and described in Patent No. 758,927, issued to me upon May 3, 1904.

It was found upon experiment that it was difficult to mold a body as large as a railway-tie of clay, owing to the fact that it was liable to crack and warp before so large a body could dry. To obviate this difficulty, I have devised the tie shown in the accompanying drawings, wherein—

Figure 1 is a side elevation of a railroad-tie constructed in accordance with the invention, showing a pair of rails in section thereon. Fig. 2 is a plan view of the parts shown in Fig. 1. Fig. 3 is a longitudinal vertical section of the tie upon line xx of Fig. 1, and Fig. 4 is a transverse vertical section of the tie.

Like numerals designate corresponding parts in all of the figures of the drawings.

It is the object of the present invention to provide a railway-tie made in sections and having improved means for binding said sections together, whereby said sections are of such size that they will readily dry without cracking or warping.

In the accompanying drawings the numeral 5 designates the central section of the tie, while the numerals 6 designate the outer sections of the tie. All of these sections have a channel 7 formed longitudinally therethrough, while molded in the sections 6 are wooden blocks 8. Shoulders 9 are formed upon the sections 6 and serve to prevent lateral movement of the rails 10 by engaging the sides of the bases 11 thereof. Resilient cushioning-strips 12 are inserted beneath the base-flanges of the rails and serve to cushion the same. The ends of the sections are recessed, as at 13, and when it is desired to secure said sections together to form a complete tie said recesses are filled with cement 14. Tie-rods 15 are then passed longitudinally through the channel 7, said tie-rods

having heads 18 upon one end thereof, which rest, when the parts are in their assembled position, against a plate 19, which closes one end of the channel 7. Said channel 7 is then filled with grout, (indicated at 20,) after which a plate 21 is placed in position to close the other end of the channel 7, and nuts 22 are threaded upon the ends of the tie-rods to bind all of the parts together. These tie-rods are made in two sections, said sections being joined by a hook-and-eye joint at 25. This results in imparting a limited flexibility to the tie as a whole and reduces the strain upon the rolling-stock which passes over the track.

The scarcity of lumber renders the old wooden tie very expensive, and a tie which may be made from a suitable clay has long been sought; but, as before stated, the difficulties met with in drying clay bodies of the size of a railroad-tie have rendered it impossible to produce a satisfactory tie of this character. By virtue of the construction herein set forth I am enabled to make a tie of this character without having it crack or warp in the making.

While the elements shown and described are well adapted to serve the purposes for which they are intended, it is to be understood that the invention is not limited to the precise construction set forth, but includes within its purview such changes as may be made within the scope of the appended claims.

What I claim is—

1. A railroad-tie formed of a plurality of hollow molded sections, means for binding all of said sections together end to end and a filling of plastic material adapted to harden or set, in said hollow sections.

2. A railroad-tie formed of a plurality of molded sections having channels formed therethrough, means for binding said sections together end to end, and a filling of grout in said channels.

3. A railroad-tie comprising a plurality of molded sections, and flexible members for binding all of said sections together end to end.

In testimony whereof I affix my signature in presence of two witnesses.

JOHN MURPHY.

Witnesses:

FRANK G. CAMPBELL,
A. L. PHELPS.
